UNITED STATES PATENT OFFICE.

JOSE LASTRA CANAL, OF HABANA, CUBA, ASSIGNOR TO FRANCISCO TORRES GENER,
JOSE TORRES GENER, AND DA JUANA TORRES GENER, OF HABANA, CUBA.

DISPLAY RECEPTACLE.

Application filed May 1, 1922. Serial No. 557,714.

To all whom it may concern:

Be it known that I, JOSE LASTRA CANAL, citizen of Spain, residing at Habana, in the island of Cuba, have invented certain new and useful Improvements in Display Receptacles, of which the following is a specification.

This invention relates to display receptacles and more particularly to cabinets or boxes for cigars.

An object of the invention is the provision of a display receptacle consisting of a main container and a plurality of auxiliary containers hinged to the main container to permit closure within the main container, and further permit the auxiliary containers to be arranged on the outside of the main container for display purposes.

A further object of the invention is the provision of an interior display device having a plurality of compartments which may be employed to display different styles or makes of cigars.

A further object is the provision of a plurality of separate containers which may be arranged in attractive display condition and entirely closed within the main container.

In the accompanying drawings, I have shown one embodiment of the invention. In this showing:

Figure 1 is a perspective view showing the parts in position for display,

Figure 2 is a similar view showing the auxiliary containers in closed position,

Figure 3 is a vertical transverse sectional view,

Figure 4 is a longitudinal sectional view on line 4-4 of Figure 3, and,

Figure 5 is a perspective view of a supporting tray.

Referring to the drawings, the reference numeral 1 designates the base or bottom section of the main container. A cover 2 is secured thereto by means of hinges 3. The base is provided with a slidable locking member 4 adapted to be received in a lock keeper 5, carried by the cover. Transverse supporting members 6 are arranged at opposite ends of the bottom of the base section. Longitudinal strips 7 are arranged at the front and back of the bottom of the base section. A pair of auxiliary containers 9 are secured to the top of the side walls by means of hinges 10. When in closed posi-

tion, these containers rest upon the supporting strips 6 and 7, and substantially fill the upper portion of the base. As shown, the bottoms of the auxiliary containers are provided with beveled edges 11 and 12, which are adapted to engage each other when in closed position. A handle 13 is provided on the bottom of one of the auxiliary containers.

Each of the auxiliary containers is provided with a cover or top 14, secured to the body portion by means of hinges 15. The auxiliary containers are provided with locks 16, adapted to engage suitable keepers 17 carried on the covers. The interior of the auxiliary containers is provided with supporting strips 18. In Figure 5 of the drawings, there is shown a separating member 19 which is adapted to fit within the auxiliary container. A row of cigars 20 may be arranged in the bottom of the auxiliary container and the separating strip 19 then put in position. A second row 21 of cigars may be arranged on top of this strip. The strip is provided with a cut out portion 22 at one corner to permit it to be grasped by the finger of the operator to obtain access to the lower row of cigars. The main container may be filled with a lower row 23 of cigars upon which is arranged a supporting strip 24, and a second row of cigars 25 arranged thereon. A separating strip 26 may be arranged above this layer of cigars to prevent injury by the auxiliary containers. As shown, the main cover 2 is provided with recesses 27 adjacent the hinges 10 of the auxiliary containers.

It is to be understood that the form of the invention herewith shown and described is to be taken as a preferred example of the same, and that various changes in the shape, size, and arrangement of parts may be resorted to without departing from the spirit of the invention or the scope of the subjoined claims.

Having thus described my invention, I claim:

1. A display box comprising a main receptacle, a cover hinged thereto, a plurality of auxiliary receptacles hinged to the inner side of the upper edge of the main receptacle and adapted to be arranged beside said main receptacle when in open position, said auxiliary receptacles being further adapted to be arranged within said main receptacle in an

inverted position when closed, the cover being provided with recesses for the reception of the hinges of the auxiliary receptacles, and means for supporting said auxiliary receptacles in closed position.

2. A display box comprising a main receptacle, a cover hinged thereto, a plurality of auxiliary receptacles hinged to the inner side of the upper edge of the main receptacle and adapted to be arranged beside said main receptacle when in open position, said auxiliary receptacles being further adapted to be arranged in said main receptacle in an inverted position when closed, the cover being

provided with recesses for the reception of 15 the hinges of the auxiliary receptacles, and supporting strips secured to the side and end walls of the main receptacle adjacent the bottom thereof and adapted to form a support for said auxiliary receptacles when the 20 auxiliary receptacles are in closed position.

In testimony whereof I affix my signature in presence of two witnesses.

JOSE LASTRA CANAL.

Witnesses:

Jose Esteve Pons,
J. A. SPRINGER.
